UNITED STATES PATENT OFFICE

156,666

BAND GRINDING MACHINE

Roland Richard Rönström, Saltsjöbaden, Stockholm, Sweden, assignor to Rolling Fabriksaktiebolag, Stockholm, Sweden, a firm

Application April 20, 1948, Serial No. 145,856

Term of patent 14 years

(Cl. D37—1)

To all whom it may concern:

Be it known that I, Roland Richard Rönström, a subject of the Kingdom of Sweden, residing at Värgårdsvägen 62, Saltsjöbaden, in Stockholm, Sweden, have invented a new, original, and ornamental Design for a Band Grinding Machine, of which the following is a specification, reference being had to the accompanying drawing, forming part thereof.

On the drawing:

Fig. 1 is a front perspective view of a band grinding machine embodying my new design;

Fig. 2 is a side perspective view thereof.

The other side, not shown, is substantially like the side shown.

I claim:

The ornamental design for a band grinding machine, as shown and described.

ROLAND RICHARD RÖNSTRÖM.
